UNITED STATES PATENT OFFICE.

PERRY BROWN, OF WILMINGTON, DELAWARE.

LIFTING-JACK.

SPECIFICATION forming part of Letters Patent No. 605,072, dated June 7, 1898.

Application filed June 6, 1896. Serial No. 594,575. (No model.)

To all whom it may concern:

Be it known that I, PERRY BROWN, a citizen of the United States, residing at Wilmington, in the county of New Castle and State 5 of Delaware, have invented a certain new and useful Improvement in Lifting-Jacks, of which the following is a specification, reference being had to the accompanying drawings.

This improvement relates to that class of 10 lifting-jacks provided with arms to receive the wheel while the axle is being oiled; and the invention consists in the peculiar construction, arrangement, and combinations of parts hereinafter more particularly described 15 and then definitely claimed.

In the accompanying drawings, Figure 1 is a side elevation of a jack constructed according to my improvement with the lever elevated and with part represented as broken 20 away. Fig. 2 is a side view of the handle detached, also with part represented as broken away.

Referring now to the details of the drawings by numerals, 1 indicates the standard of 25 a jack provided with my improvements, 2 the plunger thereof, and 3 an adjustable arm extending therefrom. To operate the plunger, I have pivoted to the standard near its base a lever 4, having a removable handle 5, 30 provided with a socket 6 to receive a tenon (shown in dotted lines in Fig. 1) on the end of the lever. The handle is provided with a wrench, formed of a fixed jaw 7 and a movable jaw 8, which latter is capable of adjustment by means of a thumb-screw 9, so as to 35 fit it to hold any sized nut. To prevent the jaw moving when adjusted, I provide a series of teeth 10 in the back of the movable jaw and the face of the handle. By this construction the nut may be unscrewed from a carriage-axle, and the handle, with the nut still

in the jaws, as shown in dotted lines in Fig. 2, may be attached to the lever and then used to operate the same and so raise the plunger, when the wheel may be made to slide sideways onto the arm 3, as indicated by dotted lines in Fig. 1, so that there is no necessity of touching the nut with the hands, and thus soiling the fingers is prevented.

I am aware that it has been proposed to 50 provide a lever for a jack with an adjustable-jawed wrench on a removable handle in which it is necessary to remove the nut from the jaws of the wrench before the two parts of the handle can be operatively united for use; 55 but with my arrangement of a deep socket in the handle adapted to receive the end of the operating-lever, even when the nut is between the jaws, the nut can be allowed to remain in the jaws of the wrench, and thus the operator need not soil his fingers by handling the nut.

What I claim as new is—

In a wagon-jack, a two-part lever for operating the same, one part being detachable 65 and the other part pivoted to the standard, the detachable part being provided with a fixed jaw and a movable jaw forming a wrench, and one of the two parts having a socket independent of the jaws of the wrench to receive 70 the end of the other part, whereby the nut of the wagon-axle may be held in the wrench while the two parts are in operative connection, substantially as described.

In testimony whereof I affix my signature, 75 in the presence of two witnesses, this 2d day of June, 1896.

PERRY BROWN.
